(57) **CLAIM**

The ornamental design for an intelligent service robot, as shown and described.

DESCRIPTION

1. Intelligent service robot
2. The title for this industry design: Intelligent service robot;
3. Possible use: This product is used for an intelligent service robot;
4. Main design point: The shape;
5. The best demonstration of the main design point: perspective view.

Fig. 1.1 is a front elevation view of an intelligent service robot showing our new design;

Fig. 1.2 is a back elevation view thereof;

Fig. 1.3 is a left-side elevation view thereof;

Fig. 1.4 is a right-side elevation view thereof;

Fig. 1.5 is a top plan view thereof;

Fig. 1.6 is a bottom plan view thereof;

Fig. 1.7 is a front, left perspective view thereof; and

Fig. 1.8 is a back, right perspective view thereof.
